Primary Examiner — Christian P. Mclean*Assistant Examiner* — Katherine E Morris(74) Attorney, Agent, or Firm — Barnes & Thornburg(57) CLAIM

The ornamental design for a correspondence kit as shown and described.

DESCRIPTION

FIG. 1 is a perspective view of the correspondence kit showing our new design,

FIG. 2 is a front view thereof,

FIG. 3 is a back view thereof,

FIG. 4 is a left elevation view thereof,

FIG. 5 is a right elevation view thereof,

FIG. 6 is a top view thereof; and,

FIG. 7 is a bottom view thereof.

The broken lines in the drawings depict portions of the correspondence kit that form no part of the claimed design. POSTBOOK® is a registered trademark owned by POSTBOOK, INC., an Indiana corporation, that forms part of the disclosure.
